PILE FEEDER

Irving F. Niles, Shaker Heights, Ohio, assignor to
 Harris-Seybold Company, Cleveland, Ohio, a
 corporation of Delaware

Application May 25, 1948, Serial No. 29,033

7 Claims. (Cl. 271—62)

1

This invention relates to improvements in pile feeders, that is to say mechanism for feeding sheets from the top of a pile. In pile feeders it is conventional practice to provide automatically operated mechanism for raising the pile step by step in order that the surface of the pile may be maintained at the proper level for cooperation with the sheet separating and forwarding means. To this end the support is attached to four cables which extend upwardly over pulleys and then downwardly to a drum that is turned through a small angle intermittently to raise the support step by step as required by the removal of sheets from the top of the pile.

When sheets that have been printed with one or more colors are to be put through a printing press the second time or are to be otherwise treated, as by being put through a folding machine, it frequently happens that the pile which may be several thousand sheets deep is uneven, due to more ink in certain areas than in others. In the case of stream feeders particularly, where the sheets are handled at their rear ends, it is important that the sheets at the top of the pile have their forward edges approximately level in order that they may move readily into the bite of the pull-out rolls.

The present invention has for its primary purpose the provision of means for quickly and easily raising or lowering one or the other of the forward corners of the pile support in order to maintain the top of the pile at its forward end level transversely.

Another object is the provision of means for this purpose which may be caused to function without interruption of the feeding operation and by means of controls accessible from one side only of the feeder.

Still another object is the provision of means for effecting the adjustment by varying the height of the mounting of the individual pulleys at the forward end of the pile.

Other objects and features of novelty will appear as I proceed with the description of that embodiment of the invention which, for the purposes of the present application, I have illustrated in the accompanying drawing, in which

Fig. 1 is an elevational side view of a feeder embodying the invention, the view being more or less diagrammatic and all parts not directly related to the invention being omitted.

Fig. 2 is a fragmental plan view of the same.

In the drawing I have shown at 10 and 11 vertical frame members which are joined at each side of the machine by horizontal frame mem-

bers 12. The pile of paper sheets, indicated at P, is carried upon a vertically movable support, which may comprise a platform 14 resting upon transverse bars 15 with longitudinal bars 16, one at each side of the machine, carrying the transverse bars.

On each of the frame members 12 there are journaled a rear pulley 17 and a forward pulley 18. Cables 19 and 20 are attached to the rear ends of the bars 16 and extend upwardly to the pulleys 17, over those pulleys and pulleys 18, and downwardly to a winding drum 21 which is keyed to a shaft 22. It should be understood that while I have referred to the part 21 as a drum, it may be constituted of a plurality of sheaves of uniform diameter keyed to the shaft 22. To the forward ends of the two bars 16 there are attached cables 23 and 24 which extend upwardly over pulleys 25 and 26 and downwardly to drum 21. The cables 19, 20, 23 and 24 are secured to the drum 21 by suitable means, and any rotation of the drum will produce equal vertical movement in all of the four corners of the support. The shaft 22 is rotated clockwise through a small angle intermittently to raise the pile support a small increment, the winding mechanism being under control of a feeler, not shown, normally engaging the upper surface of the pile. Mechanism for this purpose is well known in the art and hence is not illustrated herein.

Pulleys 25 and 26 turn on pivots 27 and 28 supported by bifurcated subframes 29 and 30. These subframes are movable to adjust pivots 27 and 28 up or down. Preferably they are mounted on pivots 31 and 32 supported in brackets 33 and 34 bolted to frame members 12. The forward ends of subframes 29 and 30 are mounted for adjustment vertically. Subframe 29 is provided with a noddy pin 35 that is bored and threaded to take a screw 36 which extends through a smooth clearance hole in a stud 37 that is mounted in the frame of the machine.

A worm gear 38 is keyed to screw 36 above stud 37. The screw has a head 39 which bears on the worm gear 38, by which means the load is transferred to stud 37. 40 is a short shaft which is journaled in the frame of the machine. It has a squared end 41 for the reception of a crank by means of which it may be turned through any desired angle. Shaft 40 carries a worm 42 which meshes with worm gear 38. Consequently as shaft 40 is turned in one direction or the other the screw 36 is rotated and raises or lowers the forward end of subframe 29, which of course elevates or lowers the forward end of bar

16 on that side of the machine without in any way interfering with the operation of drum 21.

The means for individually adjusting the forward end of subframe 30 is similar in most respects to that for adjusting subframe 29, there being a vertical screw to which is keyed a worm gear 44 and a worm 45 that is fixed upon a shaft 46.

Shaft 46 however extends entirely across the machine and projects outwardly alongside and parallel to shaft 40, where it is provided with a squared end 47 of the same dimensions as squared end 41. A single crank can be applied to either of these squared ends for effecting adjustment of the subframes 29 or 30.

At the forward end of the pile there are pile guides 50 the upper extremities of which are deflected forwardly, so that as the uppermost sheet of the pile is floated off and carried forward by an air blast its forward edge is guided upwardly into the bite of a pair of pull-out rolls. As illustrated herein these rolls comprise a lower continuous roll 51 which may be driven continuously or intermittently, and a series of disks 52 together constituting the upper roll, these disks being carried at the outer ends of arms 53 fixed upon a rock shaft 54. Disks 52 are lowered intermittently at the proper time in the cycle for pressing the sheet against the driven roll 51, thereby providing traction for enabling the roll 51 to drive the sheet forward over a short table 55 and onto a series of traveling tapes 56 by which the sheets are conveyed forwardly either singly or in a stream.

Having thus described my invention, I claim:

1. In a pile feeder, a frame, an elevator pile support movable up and down in said frame, pulley and cable mechanism for raising said support step by step, said mechanism comprising cables attached to the forward end of said support and a pair of pulleys over which said last named cables run, and a separate adjustable means for varying the height of each of said pulleys, said adjustable means being operable while said pulley and cable mechanism is in operation.

2. A pile feeder as defined in claim 1, comprising means accessible from one side of said feeder for actuating both of said adjustable means.

3. A pile feeder as defined in claim 1, comprising parallel shafts journaled in said frame, each of said shafts being adapted to actuate the adjustable means for one of said pulleys, and said shafts having manual actuating means at the same side of the feeder.

4. In a pile feeder, a frame, an elevator pile

support movable up and down in said frame, pulley and cable mechanism for raising said support step by step, said mechanism comprising cables attached to the forward end of said support and a pair of pulleys over which said cables run, two subframes mounted on said frame, one at each side thereof, in which said pulleys are carried, and means for adjusting said subframes up and down individually.

5. A pile feeder as defined in claim 4, wherein said adjusting means comprises vertical screws carried by the frame running through nuts on the subframes, and means for turning said screws individually.

6. In a pile feeder, a frame, an elevator pile support movable up and down in said frame, a cable attached to each of the two front corners and each of the two rear corners of said support, a winding drum adapted to be actuated step by step to which all of said cables are connected, pulley means over which the cables attached to the rear corners of said support run on their way to said drum, a pair of pulleys over which the front cables run on their way to said drum, separate subframes on which said last named pulleys are mounted, and means for adjusting said subframes individually up and down, whereby said support may be warped by manipulation of said adjusting means to maintain the forward top edge of the paper pile substantially horizontal.

7. In a pile feeder, a frame, an elevator pile support movable up and down in said frame, four cables attached respectively to the four corners of said support, mechanism for winding said cables simultaneously and to the same degree, pulleys over which said cables run between said support and said winding mechanism, and adjustable means for raising or lowering one of said pulleys to vary the relative height of one corner of the support.

IRVING F. NILES.
